WILLIAM G. BEDFORD, OF PHILADELPHIA, PENNSYLVANIA.

Letters Patent No. 71,266, dated November 26, 1867.

IMPROVEMENT IN HOSE-COUPINGS.

The Schedule referred to in these Letters Patent and making part of the same.

TO ALL WHOM IT MAY CONCERN:

Be it known that I, W. G. BEDFORD, of Philadelphia, Pennsylvania, have invented an improved Coupling for Hose, Pipe, etc.; and I do hereby declare the following to be a full, clear, and exact description of the same.

My invention consists of a coupling, composed of two sections, constructed and adapted to each other in the peculiar manner fully described hereafter, and applied to hose or other tube, as well as to rods, for the purpose of readily connecting the same together and disconnecting them from each other.

In order to enable others skilled in the art to make and use my invention, I will now proceed to describe its construction and operation, reference being had to the accompanying drawing which forms a part of this specification, and in which—

Figure 1 is a sectional elevation of my improved coupling.

Figure 2, a detached sectional view.

Figure 3, a section on the line 1-2, fig. 1; and

Figure 4, a section on the line 3-4, fig. 1, showing the parts in a position they occupy when the two sections of the coupling are being connected together.

The improved coupling consists of the two sections A and A', the former being enlarged from the point y to its outer end, so as to form a socket, a, for the reception of a tubular projection, a', on the section A' of the coupling. Within the socket a is a shoulder, b, on which rests a packing-ring, c, and on the outside of the section A is an annular projection or collar, f. Within the socket a, at opposite sides of the same, are two lugs or projections, d d, having inclined lower edges, x, the lugs being at such a distance apart as to permit the passage between them of projections or lugs e e on the opposite sides of the tubular projection a' of the section A', each of the said lugs being inclined at the upper edge, as shown in the drawing, and having, on the outside, teeth i i, for a purpose described hereafter. In a recess in the section A fits a curved spring-catch, n, which is secured at one end to the section, and has at the other end a projection, m, with an inclined face and an abrupt shoulder, the said projection extending through an opening, s, into the socket a, and catching into the ratchet-teeth on the lugs e e of the tubular projection a'. When the two parts or sections of the coupling have to be secured together, the projection a' is introduced into the socket a until its end rests on the packing-ring c; it is then turned so as to bring the lugs e under the lugs d, and their inclined edges in contact with each other, the end of the tubular projection being thus forced firmly against the packing-ring c. As the section A' is turned in the direction of its arrow, fig. 3, the spring-catch will slide readily over the toothed edge of the adjacent lug e, but will effectually prevent the turning back of the section A' until the spring-catch is released from the ratchet-teeth, when the two sections can be readily uncoupled.

The above-described coupling, although especially applicable to hose, may be used in connection with other tubes or pipes, or in connection with rods used for boring wells, and for other purposes.

I claim as my invention, and desire to secure by Letters Patent—

1. A coupling, consisting of a section A, with a socket a, shoulders b, and lugs d d, and a section A', having a tubular projection a', lugs e e, and shoulder f, the two sections being constructed and adapted to each other substantially as described.
2. The combination of the spring-catch n, on the socket A, with the tubular projection a' and its ratchet-teeth i i.

In testimony whereof I have signed my name to this specification in the presence of two subscribing witnesses.

Witnesses:

C. B. PRICE,

CHAS. E. FOSTER.
